UNITED STATES PATENT OFFICE.

FREDERIC B. CLARK, OF ENGLEWOOD, NEW JERSEY.

ACROBATIC TOY.

Application filed February 13, 1922. Serial No. 536,020.

To all whom it may concern:

Be it known that I, FREDERIC B. CLARK, a citizen of the United States, and a resident of Englewood, in the county of Bergen 5 and State of New Jersey, have invented certain new and useful Improvements in Acrobatic Toys, of which the following is a specification.

This invention relates to acrobatic toys 10 and especially to that type in which a mannikin is employed to perform various antics.

One of the objects of this invention is the provision of simple, adjustable means for causing a mannikin to be hurled through 15 the air, while free from control, in imitation of a human trapeze performer, and for varying the acrobatics which said mannikin accomplishes.

A further object of this invention is the 20 provision of a simple toy figure or mannikin which is adapted to catch, and to release a trapeze or bar, whereby its journey through the air is terminated or begun respectively.

25 Other objects of this invention will appear as the description progresses. In the drawings accompanying this specification and illustrating the preferred form of my invention, Fig. 1 is a perspective view of the frame or gymnastic apparatus on which the mannikin performs. Fig. 2 is a vertical section of a portion of said frame, showing in dotted lines, some of the positions assumed by said mannikin during the performance of one of its tricks. Figs. 3, 4 and 5 are similar views showing other tricks which may be performed by the mannikin. Fig. 6 is an end view of the spring 30 for holding the mannikin in its initial position. Fig. 7 is a vertical section on the line 7-7 of Fig. 6. Fig. 8 is a front view of the mannikin, showing the pivotal points thereof. Fig. 9 is a front view of one of the sliding clamps. Fig. 10 is a vertical section of the same on line 10-10 of Fig. 9, and Fig. 11 is a perspective view of one form of the end of the collapsible or folding members of the frame.

The lowermost horizontal members 20 of 50 the said frame are widened at the ends thereof to form the loops 21 whereby a firm base is provided and the frame prevented from tilting or falling during the opera-

tion of the device. At the ends of the frame, the upstanding post members 22 55 serve to support the uppermost horizontal members 23, on which trapezes such as 24 and 25 are suitably mounted. The central posts 26 each have a number of holes as 27, 28 and 29 therein in which a suitable pin or cross bar 30 may be detachably inserted for the purpose which will be more fully described hereinafter.

For allowing the adjustment of the cross pin 30 longitudinally of the frame, the upper end of each of the uprights 26 is suitably slotted as at 31 while the member 23 is slotted as at 32, a suitable screw or bolt as 33 being arranged to pass through both of said slots 31 and 32 for connecting said member 26 adjustably to said member 23. At the lower corners of said frame, suitable braces 34 are provided to connect the end posts 22 to the lower member 20, the ends of said braces and of the members 22 and 26 terminating in hooks as 35, (Fig. 11) if desired, whereby the hook members may be readily attached to or detached from a suitable screw bolt or rivet 36. The pivoted or permanently secured ends of said foldable members 22, 26 and 34 are each fastened to the member to which it is pivoted by means of a suitable screw bolt or rivet. In that form of the frame in which the hook 35 is omitted, a suitable removable screw 85 bolt is substituted at the ends of said foldable members, for allowing the removal of said ends when said frame is to be collapsed.

It will be readily understood that to fold up or collapse the frame, the hooked ends 35 of the members 22, 24 and 26 are detached from the bolts or rivets 36, and are folded back on the horizontal members 20 and 23 as desired. It will also be understood that the cross bar or pin 30 may be 95 removed from any of the holes in the post 26 into which it may have been inserted and then positioned along the upper member 23 at any desired point thereof, by inserting said pin 30 through the holes 37 100 of the movable clamps 38. Said clamps may be secured to said upper member 23 at any desired point thereof by means of the set screws 39, or said clamps may be entirely removed when desired from said member 23 105 and attached instead to the post 26 whereby

still further adjustment of the pin 30 vertically and horizontally is made possible.

For holding the mannikin 40 in its initial position in which it is ready to begin the performance of its tricks, the spring 41 is provided, said spring being secured to the member 23 as by means of the screw bolt 42. The mannikin 40 comprises a body portion having the head 43 thereon simulating the human head, forearms 44 pivoted to said body by means of a suitable pin 45, and a U-shaped member 50, preferably of wire, terminating in the L-shaped hands 46, the portion 51 of said hands serving as a pivot about which said hands are hinged to said forearms. The legs 47 of said mannikin are pivoted on the cross bar 52 thereof, to the lower end of said body member 40, and terminate in the hooks 48.

It will be noted that not only are the forearms 44 permitted to swing about the body member, but that the hands 46 are adapted to pivot about the said forearms, and that the legs 47 are also adapted to swing about the body member.

To perform the trick illustrated in Fig. 2, the mannikin is hooked on to the trapeze 25 by means of the L-shaped hands 46, and is then drawn back in between the halves of the spring 41, whereby the mannikin is held in its initial position. On the release of said mannikin, the swing of the trapeze carries the mannikin to a point where the upper ends of the hands 46 strike the cross bar 30, whereupon said hands 46 are forcibly released from the trapeze bar, and drop back about their pivots 51. The mannikin however, continues its swing until it reaches the position shown by the dotted lines at 53, Fig. 2, in which the lower end of the body 40 strikes the bar of trapeze 24, whereupon the legs 47 are suddenly jerked upwardly about their pivots 52 and hook themselves about the trapeze bar 24, the mannikin assuming the position shown by the dotted lines at 54, in which the mannikin hangs suspended from the trapeze with its head down.

Due to variations in the swing of the trapeze 25, and in the arrangement of the mannikin thereon, the said mannikin, after striking the bar 30, often performs a somersault and a half (not illustrated) before catching on to the second trapeze 24.

For the performance of the trick shown in Fig. 3, a second cross pin 30' is inserted in the holes 37 of the clamp 38, which has been previously adjusted to the proper position by trial along the upper member 23, the cross pin 30 being inserted through the proper one of the holes in the post 26 so that the initial swing of the trapeze 25 causes the cross bar thereof to strike the pin 30. The sudden shock of the blow causes the mannikin to be thrown upwardly

about said pin 30 to the position shown at 55, Fig. 3, wherein the arms 46 become disengaged from the trapeze 25 and the legs 37 are thrown around the auxiliary cross piece 30', the remaining uninterrupted movement 70 of the mannikin being effective to cause the legs 47 to become hooked around the cross bar 30' due to the force of the initial swing, whereby said mannikin assumes its final position illustrated by the dotted lines at 56, 75 Fig. 3.

The trick illustrated in Fig. 4 is performed in a somewhat similar manner, excepting that the cross bar 30' is removed, so that when the trapeze bar 25 strikes the 80 cross bar 30, the mannikin is thrown about said bar 30 through a circular path backwardly toward the position which the trapeze bar assumes on its backward swing, said mannikin passing through the position 85 shown by the dotted lines at 57, Fig. 4. The backward movement of the mannikin is interrupted when the body member 40 thereof impinges against the cross bar of the trapeze 25, assuming the position indicated 90 at 58 wherein the legs 47 are thrown around the trapeze bar, after which said mannikin drops down to the final position shown at 59.

For the performance of the trick shown 95 at Fig. 5, the auxiliary cross bar 30' is inserted through the holes 27 in the posts 26. The sudden impact of the trapeze 25 against the cross bar 30 throws the mannikin upwardly about the bar 30 as in the trick illustrated in Fig. 4, into the position shown by the dotted lines at 60, Fig. 5, the auxiliary cross bar 30', however, interrupting the backward movement of the mannikin, so that the legs 47 hook themselves about 100 said bar 30', as illustrated.

From the above description of the various tricks performed by the mannikin, it will be apparent that said mannikin moves through space entirely uncontrolled for an 105 appreciable interval of time, with neither the hands nor the legs thereof in contact with any part of the frame, whereby the effect produced on the observer is that one or more somersaults have been turned by the 115 mannikin.

The cross bars 30 and 30' are made adjustable to various positions, a series of holes as 61 are provided in the member 23 from which the trapeze 25 may be hung, and 120 adjustable clamps 38 also provided for the purpose of enabling the operator to determine by himself by experiment the exact position of the various parts of the apparatus which may be necessary for the performance of any trick. The monotonous repetition of the same trick is thereby avoided, while zest is added to the performance by the attempt of the operator to make the trick invariably successful, which will have 125 130

pen when the correct positions of the adjustable parts are reached, and in addition, the operator of the toy is enabled to discover new tricks by varying the position of 5 the cross bar or mannikin and of the cross bar 30' on which the mannikin may be made to catch.

It is obvious that various changes may be made in my improved toy without departing from the spirit of the invention. 10 Illustrations of the possible changes include the variation of the frame construction, and of the means on which the mannikin catches hold at the finish of its trick. The means illustrated for this purpose may be made of 15 magnetic material, whereby the successful finish of the trick is assured, when the hands or legs of the mannikin are attracted.

I claim:

20 1. In a toy of the character described, a trapeze arranged for manual swinging thereof, means for swingably supporting said trapeze, a mannikin, means on said mannikin removably engaging said trapeze 25 and means interposed at a point intermediate of the beginning and end of the normal swing of said mannikin for interrupting the swinging of said trapeze for discharging the mannikin from said trapeze.

30 2. In an acrobatic toy, a trapeze, a mannikin comprising a body member and swingable hands and legs adapted to engage said trapeze, and means positioned in the path of said trapeze, intermediate of the ends of the 35 normal swing of said trapeze for interrupting the swing thereof and for throwing said mannikin therefrom.

3. In combination with a frame, a trapeze carried by said frame, a bar on said frame, 40 a mannikin, means on said mannikin for removably engaging said trapeze, and means in the path of said trapeze for causing said mannikin to leave said trapeze before the termination of the normal forward swing 45 thereof and for directing said mannikin toward said bar.

4. In combination with a collapsible frame, a swingable trapeze carried by said frame, a cross bar on said frame, a mannikin adapted for suspension from said trapeze comprising a body member and hook hands and legs pivoted to said body member, and a second adjustable cross bar adapted to be positioned in the path of said 55 trapeze intermediate of the ends of the normal swing of said trapeze for causing said mannikin to leave said trapeze and for directing said mannikin toward said first mentioned bar.

60 5. An acrobatic toy comprising a mannikin, swingable means, means on said mannikin whereby said mannikin may be suspended from said swingable means, and an adjustable cross bar adapted to be positioned in the path of said mannikin and said

trapeze intermediate of the ends of the normal swing of said trapeze for catapulting said mannikin back through the air.

6. In combination with a collapsible frame, a trapeze, a mannikin, swingable 70 hook hands and swingable hook legs on said mannikin for removably suspending said mannikin from said trapeze, and means for causing said mannikin to leave said trapeze and to simulate a somersault through the air 75 and for so directing said mannikin that either said hands or said legs engage said frame on the completion of said somersault.

7. An acrobatic toy comprising a collapsible frame, a cross bar carried by said frame, means on said frame for adjusting said cross bar, a trapeze, a mannikin, means on said mannikin whereby said mannikin may be suspended from said trapeze, and a second adjustable cross bar spaced horizontally from said first mentioned cross bar and arranged in the path of said trapeze intermediate of the ends of the normal swing of said trapeze.

8. An acrobatic toy comprising a collapsible frame, a trapeze carried by said frame, a cross bar, means for carrying said cross bar, adjustable longitudinally and vertically of said frame, adapted to be secured at any desired point of said frame, a mannikin 90 adapted to be suspended from said trapeze, swingable hook hands and swingable hook legs on said mannikin, and means in the path of said trapeze intermediate of the ends of the normal swing of said trapeze for causing 95 said mannikin to leave said trapeze and for directing said mannikin toward said cross bar.

9. In an acrobatic toy, a frame, a trapeze carried by said frame, a cross bar, means for 105 adjustably carrying said cross bar comprising a pair of apertured slides, and means for detachably securing said slides to a member of said frame, a mannikin, hook terminals on said mannikin whereby said mannikin is 110 adapted to be swung by said trapeze, and means for causing said mannikin to leave said trapeze at a predetermined point in the path thereof in advance of the normal end of the swing of said trapeze for causing said 115 mannikin to catch said cross bar.

10. In an acrobatic toy, a frame, a swingable trapeze carried by said frame, a mannikin, terminal members on said mannikin adapted to engage said trapeze, means for 120 obstructing said trapeze intermediate of the ends of the normal swing of said trapeze for causing said members and said mannikin to leave said trapeze, and a spring for holding said mannikin in place at the beginning of 125 its swing.

11. In an acrobatic toy, a frame comprising a vertically slotted and apertured center-post, a horizontally slotted upper member, a bolt passing through the slots of said center- 130

- post and said horizontal member, whereby said post is adjustable longitudinally and vertically of said frame, a toy figure, hooks at the extremities of said figure, means on said upper member for swinging said figure when said hooks engage said last mentioned means, and means attachable to said center-post for interrupting the swing of said figure before the completion of said swing.
12. In an acrobatic toy, a frame, swingable means removably attached to the upper portion of said frame, a mannikin, means for holding said mannikin in its initial position at the beginning of the swing of said swingable means in engagement with said swingable means, and means independent of said swingable means for striking said swingable means during the swing thereof, where-

by said mannikin is disengaged from said swingable means and is caused to simulate 20 acrobatic tricks.

13. In an acrobatic toy, a swingable trapeze, a toy figure, means on said figure for removably engaging said trapeze, means for interrupting the swing of said first 25 trapeze for violently separating said figure from said trapeze and causing said figure to hurtle uncontrollably through the air, and means engageable by the trapeze engaging means of said figure near the end of the air 30 journey of said figure.

Signed at New York, in the county of New York, and State of New York, this 11th day of February, A. D. 1922.

FREDERIC B. CLARK.
